Des. 203,362

Patented Dec. 28, 1965

203,362

AUTOMOBILE WINDSHIELD DEFROSTER OR SIMILAR ARTICLE

William P. Richardson, Greenwich, Conn., assignor to
Empire Brushes, Inc., Port Chester, N.Y., a corporation
of New York

Filed Dec. 21, 1964, Ser. No. 83,103

Term of patent 14 years

(Cl. D62—2)

FIG. 3

FIG. 1

FIG. 2

FIG. 1 is a top plan view of an automobile windshield defroster, embodying my new design;

FIG. 2 is an elevational view taken from one side thereof, the opposite side being a mirror image of the side shown; and

FIG. 3 is a front elevational view thereof.

I claim:

The ornamental design for an automobile windshield defroster or similar article, substantially as shown and described.
